ELECTRICAL MUSICAL INSTRUMENT

Laurens Hammond, Chicago, Ill.

Application June 28, 1940, Serial No. 342,839

16 Claims. (Cl. 84—1.26)

My invention relates generally to electrical musical instruments, and more particularly to keying circuits usable in instruments of this type in which the tones are electrically originated.

This application is a continuation in part of my copending application Serial No. 157,969, filed August 7, 1937, which has matured into Patent No. 2,214,764, granted September 17, 1940.

A great deal of the appeal of the piano as a musical instrument is due to the fact that the intensity of the tones produced may be controlled by the finger touch, i. e., the instrument is "touch responsive." This touch responsive effect may be obtained in electrical musical instruments in a manner such as that disclosed in my prior Patent No. 2,126,464, but the means therein disclosed to obtain this effect is relatively costly, as several parts which are subject to wear can be made quiet in operation only by the exercise of suitable precautions. In the modified form of 20 the keying circuit shown in Fig. 28 of this patent, and likewise disclosed in my prior Patent No. 2,126,682, the mechanical structure of the keying means is greatly simplified, and an instrument incorporating this simplified key circuit has been marketed for some time under the name "Novachord."

While, strictly speaking, the instrument employing the key circuit of said Patent No. 2,126,682 is not touch responsive, musicians have discovered in playing this instrument that the touch responsive effect may be obtained in a measure by setting the controls such that the attack is comparatively slow. When the controls are set in this manner, the musician may play a selection in a manner such that the melody portion is rendered in sustained tones while the accompaniment portion of the selection is rendered in percussive tones, with the intensity of the percussive tones controlled by the player's touch. When played in this manner, the sustaining pedal is operated to obtain proper phrasing.

When played in a staccato manner, the length of time that the key is held depressed will determine the maximum intensity of the tone produced, because the attack is so slow that the tone does not reach its maximum intensity unless the key is held depressed for an appreciable length of time. Thus, the notes played in a legato manner attain maximum intensity, while the notes played in a staccato manner fail to reach maximum intensity, but attain an intensity determined by the type of staccato touch employed. That is, if the player uses an extremely 55

fast and light staccato touch, the tones produced will be of very low intensity, while if he uses a heavier, slower staccato touch the tones produced will be of intermediate intensity. If a slow or legato touch is employed, the tones will be produced at the maximum intensity for a given setting of other controls of the instrument.

The effect obtainable by playing the melody portion of the selection in a legato manner and playing the accompaniment in a detached or staccato manner, using the sustaining pedal for phrasing, is startlingly unique because the listener obtains the impression that he is listening to two instruments, one a sustained tone instrument such as a violin, horn or organ, and the other a percussive instrument such as a piano, xylophone or the like. This ability to play a sustained tone melody with a percussive accompaniment greatly enhances the musical effectiveness of the instrument by providing the musician with means for producing novel and interesting music. The fact that the musician is able, by the character of the touch employed in playing the percussive accompaniment, to control the intensity of the percussive tones, further enlarges the variety of effects which may be obtained.

My present invention is a greatly simplified form of the keying circuit disclosed in said Patent No. 2,126,682, but is based upon the general principle of operation above described, whereby the attack of the tone is made so gradual that its maximum intensity may, in a practical manner, be determined by the touch employed by the musician.

It is therefore a primary object of my invention to provide a very simple and effective touch responsive key circuit for electrical musical instruments.

A further object is to provide an improved key circuit for electrical musical instruments in which a sustaining pedal may be employed to vary the rate of decay of the tones.

A further object is to provide an improved touch responsive keying circuit for electrical musical instruments, in which there is but a single contact switch employed for each key.

A further object is to provide a keying system for electrical musical instruments in which a sustaining pedal may be operated to cause sustained tones in one register, and tones having normal decay characteristics in another register of the instrument.

Other objects will appear from the following

description, reference being had to the accompanying drawing in which:

Figure 1 is a diagrammatic view of representative portions of an electrical musical instrument showing one improved form of key circuit;

Figure 2 is an illustrative diagram, being a simplified modification of the keying circuit shown in Figure 1; and

Figure 3 is a circuit diagram showing the further modification of the keying circuit.

Referring to Figure 1, the instrument comprises an electrostatic generator assembly enclosed in a metal casing of sheet steel or the like, comprising a boxlike bottom 10, having a rigid cover 12 secured thereto by screws 14. The generator assembly comprises a plurality of vertical frame plates 16, which are held in properly spaced relation by a plurality of longitudinally extending bars 18 and rods 20. The generator assembly may be of the general construction disclosed in my prior Letters Patent No. 1,956,350, granted April 24, 1934.

The assembly of frame plates 16 is supported upon a plurality of blocks 22 of insulating material, and is held in spaced relation from the cover 12 by similar insulating blocks 24. A plurality of shafts 26 are rotatable in suitable bearings mounted in the vertical frame plates 16, and are rotated by means of a driving pinion 28, carried upon a driving shaft 30. The shaft 30 is driven at a very accurately maintained constant speed, preferably by a synchronous motor connected to the shaft by a flexible elastic coupling in the manner described in my aforesaid patent. The driving pinion 28 meshes with driven gears 32, which are preferably resiliently coupled to their respective shafts 26 in the manner disclosed in my aforesaid patent.

Phonic wheels or rotors 34 are preferably rigidly secured to their respective shafts 26, are made of brass or other suitable metal, and have their peripheries suitably formed, so as to generate a complex wave form which may be translated into sound having a pleasing tone quality. In the drawing the peripheries of the rotors are illustrated as having spaced projections 35. It will be understood that in the usual form of the instrument the number of the projections 35 upon the rotors will be correlated with their speed of rotation so that electrical impulses of the frequencies of the notes of the tempered musical scale may be generated.

It is preferable that the shapes of the notches or toothlike projections 35 on the phonic wheels be such as to produce a wave having a long series of harmonic partials of gradually decreasing amplitude, although as previously stated, their shape may be such as to produce any desired tone quality. Generally speaking, however, a tone quality fairly rich in fundamental tone and having a large series of upper partials of gradually decreasing intensity will be found most practical in an instrument of this character.

It will be understood that there will be one phonic wheel for each tone to be produced, and that in an instrument having a full piano keyboard there will be 88 phonic wheels.

The instrument is provided with a suitable keyboard or manual including a key designated D4, representative of the keys of the treble register, and key D1, representative of the keys of the bass register. Each key is adapted to close a single contact switch 36, one terminal of which is connected to a direct current potential source shown as a battery B. The other terminal of the

switch 36 is connected through a resistance 38 with an electrode 40 in the form of a narrow metal strip rigidly fixed in a metal tube 42 by means of insulating bushings 44. The inner ends of the electrodes 40 lie closely adjacent the peripheries of their respective phonic wheels 34, each with its associated phonic wheel constituting a continuously changing variable condenser.

The electrode tubes 42 are mounted for sliding movement in bushings 46 which may be pinned or otherwise rigidly secured to the cover 12, each bushing being provided with a set screw 48 so that the dimensions of the air gaps between the inner ends of the electrodes 40 and the peripheries of the phonic wheels may be adjusted, and the electrodes clamped in adjusted position. The phonic wheels, their shafts, the vertical frame plates 16 and all the metallic parts of the generator assembly associated therewith are electrically interconnected so as to constitute, in effect, a single plate common to a plurality of condensers, of which the electrodes 40 form the other plates.

The frame plates 16 are electrically connected together and have connected thereto a conductor 50 which passes through a suitable insulating grommet secured in the cover 12. The conductor 50 is connected to the grid of a vacuum tube 52 which is in the first stage of an amplifier 54. The housing or case 10, 12 is suitably grounded by a conductor 56.

Suitable means are provided to control the volume and tone quality of the output of the amplifier, such means being diagrammatically indicated at 58. The output of the amplifier is translated into sound by means of the loud speaker 58.

Upon closure of the key switch 36 associated with the key D4, the current from the battery flows through the resistance 38 to charge a condenser 60. By suitably selecting the values of the resistance 38 and condenser 60, the rate at which the potential upon the electrode 40 will be built up, may be accurately predetermined. It will be noted that one terminal of battery B is grounded. Each of the condensers 60 likewise has one plate connected to a conductor 62, which is grounded. A resistor 64 has one end connected to the conductor 62 which connects the resistance 38 with the electrode 40. The other end of the resistance 64 is connected to a contact 66 of a switch 70. The other terminal of switch 70 is connected to the grounded conductor 62. The resistance 64 is preferably of considerably higher value than the resistance 38. A resistor 72 of value several times as great as that of the resistance 64 is permanently connected between a switch terminal 66 and the grounded conductor 62.

The circuit for the key D1 is similar to that described with reference to the key D4, and similar reference characters have therefore been applied to the corresponding elements except that the grounded resistance has been designated 88 instead of 12 and the switch parts have been marked 76 and 18. The key D4 is representative of any key in the treble register of the instrument, while the key D1 is representative of any note in the bass register.

The switches 70, 76 are adapted to be operated by a sustaining pedal 82 suitably mounted on a pivot 84 and returned to normal position by a spring 86.

The sustaining pedal is illustrated diagrammatically as having an insulating bar 88 pivotally connected thereto, so that the latter will be

raised when the sustaining pedal 82 is depressed. The bar 88 is provided with an aperture 80 for the contact arms of switches 78, and a relatively larger aperture 92, for the contact arms of switches 70. In this way, upon depression of the sustaining pedal 82, the bar 88 will be raised, and during the initial portion of its upward stroke will open the switches 78, and upon continued upward movement thereof, will open switches 70.

In operation the phonic wheels will be rotated at constant speed continuously, and the instrument played in the manner of a piano or organ. Upon depression of a key, D4, for example, closure of the associated switch 36 will cause a gradual rise in the potential of the associated electrode 40. The rate at which the potential on this electrode is built up is determined by the values of the resistance 38 and condenser 60. During this period the effect of the leak to ground furnished by the resistance 64 will be relatively small because this resistance is considerably higher than resistance 38. As the potential of the electrode 40 is raised, a signal of gradually increasing amplitude will be impressed upon the conductor 50. The character of this signal will be predetermined by the shape of the periphery of the phonic wheel 34 which is rotating adjacent the energized electrode 40. The degree of amplification of the signal impressed through the conductor 50 upon the grid of the vacuum tube of the first stage of the amplifier may be controlled by the volume and tone control device 56, which may be actuated by means of a manual control, or, in addition, by a swell pedal of the type disclosed in my copending application Serial No. 91,284, filed July 18, 1936.

Upon release of the key D4, the potential upon the associated electrode 40 will drop gradually, due to leakage of the charge of the condenser 60 through the resistance 64 and switch 68, 70 to the grounded conductor 62. As a result, the strength of the signal in the conductor 50 will decay gradually at substantially a logarithmic rate. Whenever it is desired to sustain the signal for a period longer than its normal decay period, the sustaining pedal 82 is depressed, thus opening the switch 68, 70. Under these circumstances, the leakage of the charge from the condenser 60 will be very slow, the rate being determined by the values of the resistance 64 and 72 which form a series path to ground whenever the switch 68, 70 is open. Since the resistor 72 may be of high value relative to the resistor 64, the signal will decay very slowly.

Depression of a key such as D1 in the bass register of the instrument will result in operation similar to that described with reference to key D4. However, it is preferable that the value of the resistor 80 be slightly greater than that of the resistor 72, so that the decay of the bass tones will be at a slower rate than the decay of the tones in the treble register. By operating the sustaining pedal a sufficient distance to open only the switch 76, 78, the bass tones may be rendered sustaining while the tones of the treble register decay at the usual rate, whereas if the sustaining pedal is fully depressed, both the bass and treble tones will be sustained.

When the sustaining pedal 82 is depressed to the full extent, so as to open both switches 70 and 78, the intensity of the tones produced may be controlled to a reasonable degree by the length of time that the keys are held depressed. If the key is struck a very light, fast blow, the polarizing potential upon the electrode 40 will not increase

to its maximum value, since during such brief interval that the key switch 36 is closed, the condenser 60 will not have become fully charged because of the limited current flow through the resistor 38. On the other hand, if the key is held depressed for an appreciable time interval, the current flow through the resistor 38 will fully charge the condenser 60, and thus the polarizing potential upon the electrode 40 will be raised to the maximum value.

The musician may, therefore, render musical selections to give the effect of touch responsiveness. He can readily obtain this effect by holding depressed such keys as he wishes to have produce high intensity tones, and touching lightly and rapidly those keys which he wishes to have produce tones of low intensity. Of course when playing the instrument in this manner, the sustaining pedal would be depressed, usually to its full extent, so as to produce the sustaining effect on all notes. Under some circumstances the sustaining pedal may be operated to cause sustaining of the bass tones only, in which event the touch responsive effect would be less pronounced in the treble register, and notes in the treble register would therefore be played in an organlike manner.

The circuit arrangement shown in Fig. 2 is generally similar to that of Figure 1, and is illustrated as comprising keys E1 and E2 which are adapted, upon depression, to close switches 100 and 102 respectively. These switches make contact with the common bus bar 104, and are connected by resistors R1 to their respective electrodes 40, the electrode 40 being connected to ground by resistor R2 and a condenser C1.

A resistor R3 is connected between the electrode 40 and ground through a switch 106, which is adapted to be opened upon depression of a sustaining pedal 108. It will thus be apparent that the resistors R2 and R3 are in parallel when the sustaining pedal is not depressed, so as to permit the polarizing potential on the electrode 40 to drop rapidly when the sustaining pedal is not depressed, since under these circumstances both the resistors R2 and R3 constitute leakage paths for the charge on the condenser C1. When, however, the sustaining pedal 108 is depressed and the switch 106 thereby opened, the resistor R2 forms the only leakage path for the discharge of the condenser C1, and the potential on the electrode 40 will thus drop very slowly, producing a correspondingly sustained tone.

It will be understood that the key circuits will preferably be identical and individual, except that a common bus bar 104 may be used for all key circuits, and the portion of the switches 106 which is moved by the sustaining pedal may likewise be common to the switches 106 for all of the key circuits.

The resistor R1 is the primary factor determining the rate of attack, while the resistor R3 is the primary factor determining the rate of decay when the sustaining pedal is not operated, and the resistor R2 is the main factor in determining the rate of decay when the sustaining pedal is operated. Of course the value of the condenser C1 is a factor in each of these transactions. As illustrative of suitable values which may be selected for these resistors and for the condenser C1, the following have been found to be satisfactory, although it will be understood that the values selected may be varied to suit the preferences of the player: R1, 500,000 ohms;

R₂, 5 megohms; R₃, 750,000 ohms; C₁, .1 mfd. Excepting for cost limitations, the resistances R₁, R₂ and R₃ might be made adjustable. For ordinary commercial production, however, values may readily be selected which will result in the production of tones with generally acceptable attack and decay characteristics.

In Figure 3, I have illustrated a slightly modified key circuit in which the keys G₁ and G₄ operate switches 110 and 112 respectively, and the attack resistors R₁₁ are connected between the switches and the adjustable potential source B. Furthermore, the decay resistors R₁₂ and R₁₃ are connected in series instead of in parallel, and the sustaining pedal operated switches 116 complete circuits shunting their resistors R₁₂. The values of the resistors R₁₁, R₁₂ and R₁₃ may be approximately the same as those given above for resistors R₁, R₂ and R₃ respectively; although the resistor R₁₂ may preferably have a value slightly less than 5 megohms.

In view of the fact that the circuit of Figure 3 requires that the switches 110 and 112 do not have any common parts, the cost of the switches would be slightly more than the cost of the switch structure of Figure 2, because in the latter, the bus bar 104 may be common to all of the key operated switches. The three-position sustaining pedal of Figure 1 could, of course, be incorporated with the keying circuits of Figures 2 and 3. If desired, two sustaining pedals could be provided, one being effective to open the switches 106 (or switches 116) associated with all of the key circuits, while the other sustaining pedal would open only the switches associated with the key circuits of the bass register.

From the foregoing description, it will be clear that I have provided a very simple form of key circuit for electrical musical instruments, in which a certain degree of touch responsiveness is obtainable. It will be apparent that the key circuit may be used in any type of electrical musical instrument in which the intensity at which a note is sounded, is determined by a direct current polarizing potential impressed upon a terminal of the generator, or upon an electrode of a vacuum tube used to control the transmission of the signal from the generator, as shown in my aforesaid Patent No. 2,126,682.

If it is desired to have the instrument capable of producing differing tone qualities, suitable filter circuits may be included in the amplifier and provided with control switches so that selected frequencies will be attenuated. Because the phonic wheels generate tones rich in harmonics, the tone quality may be greatly varied by attenuating certain frequencies, which will result in giving the instrument individualistic tone quality characteristics. Since the key switches 36 are in the direct current portion of the circuit, there is little possibility of producing objectionable transient frequencies in the output circuit when they are opened and closed.

In the foregoing description and in the following claims, it is assumed that the polarizing source (the battery B) has its negative terminal grounded, and that a positive potential is thus impressed upon the electrode of the generator. It will be understood that the connections of the source may be reversed so that a negative potential is impressed upon the generator electrode with equivalent effects. In the following claims, therefore, the direction of current flow

and the changes in potential are specified merely in a relative, rather than absolute, sense.

It will also be apparent that the condensers 60 and C₁ may be connected between their electrodes and any point of fixed or undulating direct current potential, instead of being connected directly between their electrodes and ground. It is therefore essential merely that these condensers be "effectively" connected between their electrodes and ground, that is, that they be connected between their electrodes and some point the potential of which relative to ground is predetermined. For similar considerations, in specifying the "charging" and "discharging" of these condensers, these terms are used in a relative rather than an absolute sense. The term "ground" is also used merely as a reference potential, and is not intended to imply an actual ground potential.

While I have shown and described particular forms of my invention, it will be apparent to those skilled in the art, that numerous alterations and modifications may be made without departing from the basic principles thereof. I therefore desire in the following claims to include such variations and modifications by which substantially the same results may be obtained in substantially the same way.

I claim:

1. In an electrical musical instrument, the combination of an element having a terminal the potential of which determines the intensity with which a particular tone is sounded, a source of potential having one pole thereof connected to ground, a key, a switch operable by said key, a resistor, means connecting the other pole of said source to said terminal through said switch and resistor when said switch is closed, a condenser connected between said terminal and ground, a relatively low resistance circuit for discharging said condenser, a relatively high resistance circuit for discharging said condenser, a switch in said low resistance circuit, and a sustaining control element forming the only means for operating said last-named switch.

2. In an electrical musical instrument, the combination of an element having a terminal the potential of which determines the intensity with which a particular tone is sounded, a source of potential having one pole thereof connected to a point of fixed potential, a key, a switch operable by said key, a resistor, means connecting the other pole of said source to said terminal through said switch and resistor when said key is operated, a condenser connected between said terminal and said point of fixed potential and thus arranged to be charged through said connecting means, a relatively low resistance circuit for discharging said condenser, a relatively high resistance circuit for discharging said condenser, a sustaining pedal, and switch means operable by said sustaining pedal independently of said key to open said low resistance circuit.

3. In an electrical musical instrument having a terminal for each note to be sounded, the potential of said terminal determining the degree of loudness of the note, a key, a direct current potential source, a bus bar connected to one pole of said source, a switch operable by said key and contacting with said bus bar, a first resistor connecting said switch to said terminal, a condenser and a second resistor in parallel connected between said terminal and the other pole of said source, a third resistor and a second switch in

series therewith connected between said terminal and said other pole of said source, and a sustaining pedal for operating said second switch.

4. In an electrical musical instrument having for an individual note a terminal, the electrical potential of which controls the intensity with which that note will be sounded, a key, a source of direct current potential having one pole thereof connected to ground, a switch operated by said key to impress a potential from said source upon said terminal, a resistance element forming a connection between said switch and said terminal, a condenser connected between said terminal and ground, adjustable resistance elements connected between said terminal and 10 ground, a sustaining pedal, and means operated by depression of said sustaining pedal to adjust said adjustable resistance elements to increase the resistance thereof.

5. In an electrical musical instrument of the 20 class described, the combination of a condenser continuously variable at the frequency of a musical tone, said condenser having a stationary part and a moving part, an amplifier connected to the moving part of said condenser to amplify 25 the electrical potential changes produced therein, a source of direct current potential having a grounded terminal, a manually operable switch for connecting the other terminal of said source to the stationary part of said condenser, a resistance element connected between said switch and the stationary part of said condenser, a fixed condenser connected between the stationary part of said variable condenser and ground, a second 30 resistance element permanently connected between the stationary part of said variable condenser and ground, a third resistance element, and optionally operable means for connecting said third resistance element in series with said second resistance element.

6. In an electrical musical instrument, the combination of a condenser continuously variable at the frequency of a musical tone, said condenser having a stationary part and a moving part, an amplifier connected to the moving part of said condenser to amplify the electrical impulses produced therein, a source of direct current potential, a manually operable single pole switch for connecting said source to the stationary part of said condenser, a resistance 45 element connected between said switch and the stationary part of said condenser, a fixed condenser connected between the stationary part of said variable condenser and ground, a second resistance element in a circuit connecting the stationary part of said condenser to ground, said second resistance element having a value greater than that of said first resistance element, and optionally operable means for shunting said second resistance element.

7. In an electrical musical instrument, the combination of a plurality of electrostatic generators, means for translating into sound the impulses produced by said generators, key operated means for impressing energizing potentials upon selected ones of said generators, and selectively operable means for controlling the rate of decay of the potential impressed upon said generators, said last named means being selectively operable upon a predetermined group of 50 said generators or upon all of said generators, and comprising a circuit including a resistance for each of said generators forming a leakage path for potentials impressed thereon, manually operated means movable in one manner to

change the effective resistance of said circuits for said pre-determined group of generators, and movable in another manner to change the effective resistances of said circuits for all of said generators.

8. In an electrical musical instrument, the combination of a plurality of electrically interconnected constantly rotating tone wheel rotors having projections upon their peripheral edges, an electrode for each of said generators having a portion thereof located in close proximity to the path of rotation of the projections of said rotors, means common to all of said rotors for amplifying potential variations in any one or a plurality of said rotors, means for translating said amplified potential variations into sound, an electrical potential source having a grounded terminal, a plurality of key operated switches for selectively connecting said source of potential to said electrodes, circuits each including a resistance element for connecting said switches with said electrodes respectively, a condenser connected between each of said electrodes and the grounded terminal of said potential source, a high resistance element normally connected in parallel with said condenser, and optionally operable switch means for connecting an additional resistor in series with said resistance element.

9. In an electrical musical instrument of the 30 type which comprises a plurality of rotatable tone wheels, one for each of the notes of the musical scale within the gamut of the instrument, and each having a plurality of spaced projections about its periphery, means for rotating said tone wheels, and in which an amplifier is connected to all of the tone wheels for amplifying potential variations thereon and supplying the amplified signal to electroacoustic translating means; the combination of an electrode associated with each of said tone wheels, a source of potential having a grounded terminal, a plurality of key operated single pole switches for connecting the other terminal of said source to said electrodes respectively, electrical networks between said switches, said electrodes and ground, each of said networks including a resistor connected between the switch and its associated electrode, a condenser having one plate thereof connected to said electrode and having its other plate connected to ground, a leak resistance element permanently connected to each of said condensers for gradually discharging it; and optionally operable means for increasing the effective value of the leak resistances associated with a group of said condensers, thereby to increase the length of time necessary to discharge the condensers of said group.

10. In an electrical musical instrument having a plurality of electrostatic generators and means for amplifying and translating into sound electrical impulses produced thereby; means for individually controlling the delivery of impulses from said generators to said translating means for pre-determining the rate of attack of the tones produced by said translating means comprising: resistance means for each generator effective to determine the rate of decay of the tone, a circuit individual to each of said resistance means to change the effective resistance of said resistance means, each of said circuits including a switch, and actuating means for said switches selectively controllable to operate a pre-determined group of said switches or to operate all of said switches.

11. In an electrical musical instrument of the

class described, the combination of two groups of generators, one group for generating electrical impulses of frequencies of the treble register of the musical scale, the other group for generating frequencies of the bass register of the musical scale, means individual to each of said generators for changing the rate of decay of the impulses produced thereby, a sustaining pedal, means operated upon movement of said sustaining pedal a pre-determined distance to operate said decay changing means associated with generators of one of said groups, and to operate the decay changing means associated with generators of the other of said groups upon movement of said sustaining pedal an additional distance.

12. In an electrical musical instrument, the combination of a plurality of electrostatic generators having phonic wheels rotating at constant speeds, there being one of said generators for each of the notes of the musical scale within the gamut of the instrument, electrodes respectively cooperable with said wheels, an amplifier connected to all of said phonic wheels so as to be responsive to potential changes thereof, means for translating the output of said amplifier into sound, a source of direct current, selectively operable means individual to each of said generators to impress the potential of said source upon said electrodes, said means including a condenser and resistance network to control the rate of decrease of the potential impressed upon said electrodes, thereby to control the decay of the tones produced by said translating means, and a single optionally operable means for changing the effective value of resistance in the network associated with one of said generators, or to change the effective values of the resistances in said networks associated with said last named generator and at least one additional generator.

13. In an electrical musical instrument having a terminal the potential of which relative to ground determines the intensity of a tone produced by the instrument, the combination of a condenser effectively connected between said terminal and ground, a source of polarizing potential fixed relative to ground, a key-operated switch, a low resistance circuit completed by said switch and connecting said source to said terminal, a circuit including a high resistance ef-

fectively shunting said condenser, a second switch, a second circuit effectively shunting said condenser and including said second switch and a resistance of value lower than said high resistance, and a sustaining pedal for operating said second switch.

14. In an electrical musical instrument having a terminal the potential of which relative to ground determines the intensity of a tone produced by the instrument, the combination of a condenser effectively connected between said terminal and ground, a source of polarizing potential fixed relative to ground, a key-operated switch, a low resistance circuit completed by said switch and connecting said source to said terminal, a circuit including a high resistance effectively shunting said condenser, a second switch, conducting means effectively shunting a portion of said high resistance and including said second switch, and a sustaining pedal for operating said second switch.

15. In an electrical musical instrument having a terminal the potential of which relative to ground determines the intensity of a tone produced by the instrument, the combination of a condenser effectively connected between said terminal and ground, a source of polarizing potential fixed relative to ground, a key-operated switch, a low resistance circuit completed by said switch and connecting said source to said terminal, a high resistance and a lower resistance connected in parallel with each other and with said condenser, and sustaining pedal operated means for opening the circuit through said lower resistance.

16. In an electrical musical instrument having a terminal the potential of which relative to ground determines the intensity of a tone produced by the instrument, the combination of a condenser effectively connected between said terminal and ground, a source of polarizing potential fixed relative to ground, a playing key, a switch operable by said key, a low resistance circuit completed by said switch and connecting said source to said terminal, adjustable resistance means shunting said condenser, a sustaining pedal, and means controlled solely by said sustaining pedal to change the effective value of said adjustable resistance means.

LAURENS HAMMOND.
